UNITED STATES PATENT OFFICE.

LEWIS FINE, OF PHILADELPHIA, PENNSYLVANIA, ASSIGNOR, BY MESNE ASSIGNMENTS, TO BUDD WHEEL COMPANY, OF PHILADELPHIA, PENNSYLVANIA, A CORPORATION OF PENNSYLVANIA.

STAMPED METAL WHEEL.

1,404,382.

Specification of Letters Patent. Patented Jan. 24, 1922.

Application filed May 12, 1919. Serial No. 296,627.

To all whom it may concern:

Be it known that I, LEWIS FINE, a citizen of the United States, residing at Philadelphia, Pennsylvania, have invented certain new and useful Improvements in Stamped Metal Wheels, of which I declare the following to be a full, clear, and exact description.

This invention relates to improvements in metal wheels, particularly of the type adapted to be employed in connection with trucks, tractors, and the like.

One object of the invention is to provide a wheel of this character which is of strong but simple construction and efficient in operation.

A further object of the invention is to provide a metal wheel of the disc type having an improved arrangement of bracing elements for spacing the disc sections from each other.

A further object of the invention is to provide a wheel of this character having improved means for supporting the rim and retaining the same in position upon the wheel discs.

A further object of this invention is to provide a wheel of this character having certain improved details of construction and arrangement of the parts, which will be more fully described hereinafter.

Further objects of this invention relate to economies of manufacture and details of construction, as will hereinafter appear from the detailed description to follow.

The objects of the invention are accomplished in one instance by the devices and means described in the following specification, but it is evident that the same may be varied widely without departing from the scope of the invention, as pointed out in the appended claims.

A structure constituting one embodiment of the invention, which may be the preferred, is illustrated in the accompanying drawing forming a part hereof, in which:

Figure I is a side elevation of a wheel structure, embodying the present invention, having a portion thereof broken away.

Figure II is a transverse, vertical, sectional view taken along the line II-II of Figure I.

Figure III is a vertical, sectional view taken along the line III-III of Figure II,

and illustrating the relative position of the spacing rings with respect to each other and the hub.

Referring to the drawing, similar reference characters designate corresponding parts throughout the several views, and the sectional views are taken looking in the direction of the small arrows at the ends of the section lines.

In the embodiment of the invention illustrated herewith, 10 designates a hub provided with an outwardly extending annular flange 11 formed integral therewith and positioned adjacent one end of the hub. A pair of wheel discs 12 and 13 of similar construction are each provided with a central opening formed of such a size as to fit over the outer cylindrical portion of the hub member when assembled in position relative to each other. Cutaway portions 14 of similar size and shape are formed in the wheel discs intermediate the portions of the discs which fit over the hub and the outer peripheral portions thereof, these cutaway portions being formed in the discs in such a manner as to register with each other when the discs are in assembled position, and so positioned relative to each other as to provide radially extending spoke portions 15 positioned between adjacent cutaway portions and extending outwardly from the central portion of the wheel discs towards the peripheries thereof. Lock bars 16 provided with outwardly extending edge portions 17 and 18 are positioned within the cutaway openings 14 formed in the wheel discs, and when the various parts of the wheel structure are properly assembled, the outwardly extending edges 17 and 18 of the lock bars are bent over the outer surfaces of the wheel discs adjacent to the cutaway portions in such a manner as to form flanges engaging the outer surfaces of the wheel discs and assisting in securing the same properly in position relative to each other.

Each of the wheel discs is provided with an offset peripheral edge portion comprising a part 19 offset from the original plane of the disc, and an outwardly extending part 20 located in a plane substantially parallel to the original plane of the disc, the portion 20 terminating in a beveled edge 21 formed for a purpose which will be more fully described hereinafter.

A pair of annular plates 22 and 23 are positioned between the wheel discs adjacent the hub portion of the wheel in such a manner as to bear against the wheel discs 12 and 13 respectively. The inner and outer spacing rings 24 and 25 are positioned between the wheel discs adjacent the hub portion of the wheel and concentric with the axis thereof, the said spacing rings 24 and 25 being provided with reduced edge portions fitting against correspondingly formed edge portions upon the annular rings 22 and 23 in such a manner as to produce a rigid bracing structure for properly spacing the wheel discs 12 and 13 from each other, and assisting in retaining the same in proper relative position. A brake drum 26 provided with an inwardly extending annular flange 27, is positioned upon the inner end of the hub member in such a manner that the inwardly extending annular flange 27 bears against the outer surface of the wheel disc 13 adjacent the central portion thereof, and the brake drum, wheel hub and wheel discs are firmly secured together by means of bolts 28, or other suitable securing means, passed through registering openings formed in the annular portion 11 of the wheel hub, the brake drum, the wheel discs and the annular plates.

A plurality of T-shaped cross braces 30, each of which is provided with a main outwardly extending web portion 31 and a pair of oppositely extending flanges 32 formed upon the base portion thereof, are supported by the out-turned portions 19 of the wheel discs and spaced from each other throughout the circumference of the wheel. A rim 34 is provided with grooves 35 formed upon the inner surfaces of the side edges thereof, and the rim 34 is preferably shrunk upon the outer surface of the wheel in such a manner as to bear against the outwardly extending portions 31 of the T-shaped cross braces, and have the grooves 35 formed therein register with and fit over the beveled edges 21 of the peripheral edge portions of the discs so as to be firmly clamped in engagement therewith and prevent the rim from becoming disengaged from the outer surface of the wheel.

It will be understood from the above description that the spacing rings 24 and 25, together with the annular plates 22 and 23 co-operating therewith, provide a simple and efficient form of spacing means adapted to be positioned between a pair of wheel discs in such a manner as to properly space the same from each other, and these parts co-operate with securing bolts 28 to form a firm and rigid wheel structure wherein the wheel discs are properly spaced from each other and securely attached to the wheel hub. The lock bars 16, when secured in position 65 between the wheel discs with the opposite

edge portions 17 and 18 bent outwardly over the edges of the portions of the wheel discs formed by the cutaway openings, serve as an additional spacing means for spacing the discs from each other, and also serve as an additional means for securing the wheel discs in position relative to each other. The rim 34 is preferably shrunk upon the outer portion of the wheel in such a manner as to fit tightly thereupon, and the co-operating beveled edge portions of the disc and the grooves formed in the rim register with each other in such a manner as to provide a positively acting securing means for retaining the rim upon the outer surface of the wheel. The securing bolts 36 passed through the peripheral edge portions of the wheel discs and spaced from each other throughout the circumference of the wheel serve to secure the outer peripheral portions of the wheel 85 discs in proper position relatively to each other and draw them into close contact with the ends of the cross braces so as to assist in firmly securing the braces in position within the peripheral edge portions of the disc. 90

The wheel structure thus formed has the various portions thereof securely braced together in such a manner as to form a firm and rigid structure, which is capable of withstanding the various strains to which it 95 is liable to be subjected, while the various parts are capable of being readily formed and assembled in position to make the completed wheel.

While I have shown and described in considerable detail a specific embodiment of my invention, it is to be understood that this showing and description is illustrative only, and for the purpose of rendering my invention more clear, and that I do not regard the 100 invention as limited to the details of construction illustrated or described, nor any of them, except in so far as I have included such limitation within the terms of the following claims, in which it is my intention to 105 claim all novelty inherent in my invention broadly as well as specifically.

Having thus described my invention what I claim as new and desire to secure by Letters Patent is:

1. In a wheel structure, a pair of wheel discs provided with offset peripheral edge portions, a plurality of cross braces supported by the offset peripheral edge portions of the discs, spacing rings positioned between the wheel discs concentric with the axis of the wheel, and means for securing the wheel discs together. 120

2. In a wheel structure, a pair of wheel discs, annular plates positioned between the wheel discs, spacing rings positioned between the wheel discs concentric with the axis of the wheel, and bearing against the annular plates and means for securing the wheel discs together. 125

3. In a wheel structure, a pair of wheel discs provided with offset peripheral edge portions, a plurality of T-shaped cross braces supported by the offset peripheral edge portions of the discs, annular plates positioned between the wheel discs, spacing rings positioned between the wheel discs and bearing against the annular plates, and means for securing the wheel discs together.
- 10 4. In a wheel structure, a pair of wheel discs provided with offset peripheral edge portions, a plurality of cross braces supported by the offset peripheral edge portions of the discs, and a rim supported by the cross braces and the offset peripheral edge portions of the discs, said rim and offset edge portions being provided with co-operating mating means for preventing removal of the rim.
- 15 5. In a wheel structure, a pair of wheel discs provided with beveled edges, cross braces positioned between the wheel discs and supported thereby adjacent the edge portions thereof, and a rim having grooves formed therein for the reception of the beveled edges of the wheel discs.
6. In a wheel structure, the combination of a pair of wheel discs, each disc having its peripheral portion offset to form a peripheral flange lying in a plane offset from but 30 parallel to the plane of the disc, a plurality of cross braces mounted on said offset portions, and a rim mounted on the peripheral edges of said flanges and seated on said cross braces.

35 In testimony whereof, I affix my signature.

LEWIS FINE.
